[57] CLAIM

The ornamental design for a manifold for magnetic drive pump, as shown and described.

DESCRIPTION

FIG. 1 is a top plan view of a manifold for a magnetic drive pump showing my new design.

FIG. 2 is a left side elevational view thereof.

FIG. 3 is a right side elevational view thereof.

FIG. 4 is a front elevational view thereof.

FIG. 5 is a bottom plan view thereof.

FIG. 6 is a rear elevational view thereof.
